UNITED STATES PATENT OFFICE.

FRIEDRICH EHRMANN, OF STUTTGART-FEUBERBACH, GERMANY, ASSIGNOR TO ROBERT BOSCH AKTIENGESELLSCHAFT, OF STUTTGART, GERMANY.

CASTING APPARATUS.

Application filed June 25, 1927, Serial No. 201,456, and in Germany January 17, 1927.

This invention relates to casting apparatus and in particular to rotary casting machines in which molds for various articles to be cast are mounted or arranged on rotary tables, 5 the molds being opened and closed during the rotation of the parts, the cast articles being removed therefrom and the molten mass being injected into them, the cast articles removed therefrom also at the proper 10 stages of the movement of the table.

With the known casting machines of this type the casting molds and the devices for opening and closing them are arranged radially with respect to the axis of rotation of 15 the machine upon a rotatory table. This arrangement requires a large diameter of the table so that the horizontally movable casting molds and the operating members for them are accessible only with difficulty, especially as regards the parts located near the 20 middle portion of the table. The casting molds are open and closed by a common device formed generally by a curved guide. Owing to these circumstances the casting machines of this kind have been mostly confined to the manufacture of castings of a 25 single kind or type for one machine, so that these machines could be commercially utilized to advantage only where large numbers 30 of one and the same article or casting were to be produced.

In order to obviate these drawbacks my invention consists in so combining and arranging the casting molds of such a machine 35 and the coordinated devices for opening and closing these molds with each other in such a way that every such aggregate or group is arranged axially or substantially parallel with respect to the axis of rotation of the 40 machine. Owing to this arrangement the several aggregates or groups of the casting molds are readily accessible at all points. By such arrangement it is made possible to provide each mold with a closing device which is 45 independent of all other molds. Under my invention, the closing devices of all these molds can at the same time be connected with a driving device common to them all.

The invention is illustrated by way of example in the accompanying drawings in which Fig. 1 is an elevation partly in vertical section of a casting machine embodying my invention;

Fig. 2 is a plan of the machine, there being

shown, however, in this figure, for the sake 55 of simplicity, only one of the casting molds;

Fig. 3 is a side elevation of the machine showing the casting mold carrier in an oblique position, and

Fig. 4 is a longitudinal section through a 60 device for opening and closing a mold.

The casting molds are attached to a frame which is arranged to rotate on and around an upright standard 1. This frame consists of a horizontal ring 2 connected by oblique 65 stays 3 with a foot bearing 4. To this bearing or support is firmly connected a bevel gear-wheel 5 which meshes with another bevel gear-wheel keyed or otherwise secured to the driving shaft 6 of the machine. 70

The ring 2 forms a support for a plurality of radially arranged shafts 7 which pass through the suspension points of the casting mold carriers and are driven simultaneously by the intermediary of a device carried by 75 the standard 1. This device consists of a pulley 8, a worm-gearing 9 and a cog-wheel 10 with which mesh cog-wheels 11, one secured to the inner end of each shaft 7. In order to supply air or a gas for cooling, as 80 well as for heating the casting molds 12, the standard 1 is provided with bores 13 and 14 from which branch off tubes 15 and 16 connected by flexible tubes or hoses 17 with the casting molds. This arrangement renders it 85 possible to cool and heat the molds either all together or singly. For feeding the heating or cooling medium to the bores 13 and 14, feed pipes 133 and 144, respectively, are provided, as shown. 90

The casting molds 12 are in two parts, as shown in Figs. 1 and 3, and they are attached to frame-like carriers 18, each of which is connected with a bearing member 19 and turnable with respect to a radial axis on a 95 shaft 7. The mold carriers, being thus pivotally mounted on the frame comprising ring 2, stays 3 and foot bearing 4, can be swung into an oblique position and be fixed in the same by bolts 20 engaging holes 21 10 (see Fig. 1) arranged in a circular series in a bearing 22 mounted on the frame of the machine (Figs. 1, 2 and 3). Each bolt is provided with a grip 23 and can be withdrawn by grasping the grip. By the arrangement thus described each casting-mold group can be swung in a peripheral vertical plane, that is to say a plane tangential to the 105

frame and parallel to the axis of rotation of the frame, independently of the other groups. The grips can also be used for turning the mold carriers. Owing to the 5 possibility of turning the mold carriers into oblique positions the molds can be brought into the most favorable casting position, whereby the casting operation is facilitated and the formation of pipes or cavities is 10 obviated.

The two parts of every casting mold are secured detachably in any known manner to plates 24 guided upon rods 25 and movable in one or the other direction by means of a 15 threaded spindle 26 (see Figs. 1 and 3). Each spindle 26 has a right-handed and a left-handed thread, one for each plate 24 of a mold. For driving the spindle there is provided on it an encircling sleeve 27 which 20 carries cog-wheels 28 and 29, one at each end, and can be shifted upon said spindle but not turned thereon, being keyed or splined on said spindle for this purpose. The cog-wheel 28 is firmly secured to the sleeve 27 and, when it meshes with the cog-wheel 30 of the shaft 7, is rotated in such a direction that the mold is opened. The wheel 29, 25 however, sits loosely upon the sleeve 27 and is connected by an elastic friction clutch 31 with the sleeve 27 when this is shifted downwardly. This arrangement is advantageous for obtaining an elastic closing of the mold.

For shifting the sleeve 27 longitudinally for the purpose of throwing the cog-wheel 35 28 or 29, respectively, into gear, with cog-wheel 30, a hand-lever 32 provided with a counterpoise 33 is provided. This hand-lever is maintained in its middle position by springs 34 housed in a cylindrical casing 40 provided with a longitudinal slot for the passage of said lever 32. In order to close or open the casting mold, the lever 32 is moved downwards or upwards so that either the cog-wheel 29 or the cog-wheel 28 is 45 caused to mesh with the cog-wheel 30 of the driving shaft 7. The lever 32 is provided with yielding detent means comprising a yielding bolt or spring-catch 35 which engages a stop or recess in either end position 50 of this lever whereby the latter is retained at each end of its movement. Firmly connected with each hand-lever is a forked arm 36 connected movably at 38 with a head 37 (best shown in Figs. 3 and 4) arranged on sleeve 27.

In order to effect an automatic opening of the casting molds after a certain period of time the following device is provided:

Near the upper end of the sleeve 27 is arranged and firmly secured in place a threaded piece 39 engaged by a nut 40. The nut is, 60 however, ordinarily prevented from turning by means of a vertical guide-bolt 41 and it is combined with other parts in the following manner to form a tripping device for the le-

ver 32. Attached to the nut 40 is an arm 42 provided with a bolt 43 engaging a circularly curved slot provided in a double-lever 44. Jointed to the other end of this lever is a slotted rod 45, in the slot of which 70 two abutment members 46 and 47 can be adjusted and secured in their adjusted positions by screws or equivalent means. A lug projecting from the hand-lever 32 carries a bolt 48 also engaging the slot of the rod 45 75 and extending between said abutment members 46 and 47.

The manner of operation of the device is as follows:

Supposing that the lever 32 of any one of the aggregates or casting-groups be moved upwardly. Having arrived in its upper end-position it is held fast by the yielding detent means comprising the spring catch or bolt 35 engaging the corresponding stop or recess, and the cog-wheel 28 is thereby caused to mesh with the cog-wheel 30 of the continually rotating shaft 7. Thereby the threaded spindle which is provided with a right-hand and a left-hand thread is turned 80 in that direction which causes the opening of the corresponding mold. While this rotation, in which the sleeve 27 and the threaded member or nut 39 participate, takes place, the nut 40 and the arm 42 move upwardly 85 upon said member 39. Thereby the bolt 43 is caused to move upwardly in the curved slot of the double-lever 44 and when it has arrived at the end of the slot, the lever 44 is moved so that it depresses the rod 45 (see 90 Fig. 3). The downward movement of rod 45 is transmitted to the hand lever 32, because the abutment member 46 is thereby pressed against the bolt 48, thus forcing lever 32 downward. The elastic catch 35 is thereby released from the stop, so that the hand-lever can now be automatically moved back into its inoperative middle position by the springs 34. If desired, the elastic catch may 95 be actuated also by hand.

In practical operation the machine is rotated slowly in a horizontal plane by means of the shaft 6 which is driven by any suitable source of power. The groups or aggregates arranged radially with respect to the axis of rotation (axis of the standard 1) are conveniently accessible from all sides and the various devices and parts constituting a group or aggregate can be conveniently manipulated and attended to. As the devices 115 for opening and closing the casting molds can be attended to independently of one another, the operator is at liberty to adjust them differently from each other, so that castings of various sizes and shapes can be produced at the same time on one and the same machine.

Instead of employing mechanical means for opening and closing the casting molds, other means, such as electrically, pneumati- 120

cally or hydraulically operated means may be employed.

What I claim and desire to secure by Letters Patent is:

- 5 1. In a rotary casting machine, a rotatable frame in combination with groups, comprising casting molds and means for opening and closing the molds, arranged substantially parallel to the axis of rotation 10 of the machine, and means for adjusting each of said groups to a position oblique or inclined with respect to said axis.
- 15 2. In a rotary casting machine, a rotatable frame in combination with groups, comprising casting molds and means for opening and closing the same, said groups being mounted on the frame substantially parallel to the axis of rotation and turnable on a radial axis and means for swinging 20 each of said groups on such radial axis to a position oblique or inclined with respect to said axis of rotation.
- 25 3. In a casting machine, a frame for supporting the casting molds and parts for operating them, said frame comprising an upper annular portion, a lower foot-bearing and stays connecting the upper portion and the lower bearing, in combination with a standard engaging and supporting the bearing, and means for rotating the bearing on the standard.
- 30 4. In the combination set forth in claim 3, a gear-wheel arranged at the lower part of the foot-bearing and power shaft provided with a gear-wheel engaging the gear wheel on the foot-bearing.
- 35 5. In a casting machine, a rotatable frame in combination with vertical groups, comprising molds and means for operating them, each group being turnably mounted 40 on the frame, independently of the other groups, the operating means for each mold being independent of the other mold-operating means.
- 45 6. In a casting machine, a standard, a rotatable frame revolvably mounted on said standard, and molds and their operating means mounted on the frame substantially parallel to the axis of rotation, in combination 50 with operating shafts arranged radially with respect to the standard, means for simultaneously rotating the shafts arranged on the standard, and means for transmitting the movement of the shafts to the mold operating means.
- 55 7. In a casting machine, a mold mounted on the frame of the machine and formed of two parts, a screw spindle engaging said mold and provided with a right-hand 60 thread engaging one mold-part and a left-hand thread engaging the other, in combination with a double gear-wheel shiftably mounted on the screw-spindle, a rotary shaft on the machine frame having a gear-wheel fixed thereon and means for shift- ing the double gear-wheel to cause one or the other of its gears to engage the gear-wheel on the rotary shaft.
- 70 8. In the combination set forth in claim 7, a lever connected to the double gear-wheel to shift the same from one to the other position of engagement with the gear-wheel on the rotary shaft, in combination with means to yieldably hold the same in an intermediate position of non-engagement. 75
- 75 9. In the combination set forth in claim 7, a lever connected to the double gear-wheel to shift the same from one to the other position of engagement with the gear-wheel on the rotary shaft, and means to retain the lever in each shifting position, in combination with means operated by the rotation of the double gear-wheel to release the lever from the shifting position and thereby to release said double gear-wheel from engagement with the gear-wheel on the rotary shaft. 80
- 85 10. In the combination set forth in claim 7, a lever connected to the double gear-wheel to shift the same from one to the other position of engagement with the gear-wheel, on the rotary shaft and yielding means to hold said lever in an intermediate position, in combination with a nut movably threaded on the screw-spindle carrying the double gear-wheel, means connecting said nut with the lever, and means operated by the nut to release the lever from its upper or lower position when the nut reaches the end of its travel in either direction. 90
- 90 11. In a casting machine as set forth in claim 7, a sleeve slidably mounted on the screw-spindle and secured against rotation thereon, a double gear-wheel secured to the sleeve, and a lever connected with said sleeve 105 for shifting the same in one or the other direction.
- 100 12. In a casting machine, a mold mounted on the frame of the machine and formed of two parts, a screw-spindle engaging said mold, formed with right-hand thread engaging one mold-part and a left-hand thread engaging the other, a double gear-wheel shiftably mounted on the screw-spindle, a rotary shaft on the machine-frame having a gear-wheel fixed thereon and arranged to mesh with one or the other of the gears of the double gear-wheel, in combination with a lever on the frame, connected with the double gear-wheel, and means for yield- 110 ably retaining the lever at the end of its movement in either direction, a nut threaded on the screw-spindle, and means arranged between the nut and the lever to release the lever from its end position. 115
- 115 13. In the combination as set forth in claim 12, means for yieldably maintaining the lever for shifting the double gear-wheel in an intermediate position. 120
- 120 14. In the combination as set forth in 130

claim 12, a yielding catch on the operating lever arranged to engage stops or detents on the machine-frame at the ends of its movement, means for yieldably holding the lever in an intermediate position, and means operated by the nut to release the yielding catch as the nut reaches the end of its travel

15. In a casting-machine a mold mounted on the frame of the machine and formed of two parts, a screw-spindle engaging said mold and formed with a right-hand thread engaging one mold-part and a left-hand thread engaging the other, a double gear wheel shiftably mounted on the screw-spindle, a rotary shaft on the machine-frame having a gear-wheel secured thereon and arranged to mesh with one or the other of gears of the double gear-wheel, in combination with a lever connected with the double gear-wheel, and yielding detent means for holding the lever in position at the ends of its movements, means for yieldably urging the said lever to an intermediate position, a nut threaded on the screw-spindle, a second lever and connections between the same and the nut for tripping said second lever when the nut has reached a predetermined upper or lower position, and a tripping device operated by said second lever and arranged to actuate the first lever at a predetermined part of its upward or downward movement, to release said first lever from engagement with the yielding detent means

35. In the combination as set forth in claim 7 a shiftable sleeve encircling the

screw-spindle and secured against rotation thereon, one gear-wheel being fixed to the sleeve while the other gear-wheel is connected to said sleeve by an elastic friction-clutch.

17. In a casting machine, a standard, a rotatable frame mounted on said standard, and carrying frames and molds and operating means therefor mounted in said carrying frames, said carrying frame being pivotally mounted on the frame and substantially parallel to the axis of rotation, in combination with means for turning each group of molds and operating means on its pivotal axis.

18. In a casting machine, a frame rotatable on a vertical axis, in combination with groups, each comprising a casting mold and means for opening and closing the mold, arranged substantially in a peripheral plane parallel to the axis of rotation of the machine, each of said groups being pivotally mounted on and turnable into an oblique position with respect to said frame, and independent means for each group for fixing the same in any position of adjustment.

19. In a casting machine, a rotatable frame in combination with a plurality of groups, each comprising a mold and means for opening and closing the same, motive means for operating the opening and closing means and independent means for each group for coupling each opening-and-closing means with the motive means.

In testimony whereof I hereunto affix my signature.

FRIEDRICH EHRMANN.
